AUTOMATIC FIRING FLARE

Otto Gentzel, Monticello, N. Y., assignor of one-third to Harold Sturgis and one-third to Ruth Silberman, both of Monticello, N. Y.

Application February 11, 1937, Serial No. 125,340

7 Claims. (Cl. 102—24)

This invention relates to an aerial flare adapted to be fired automatically by an impact sufficient to injure a vital part of a plane or other conveyance of the flare, by submersion, by impact through dropping as well as manually.

Another object is to provide a construction wherein the automatic firing is accomplished individually or by a combination of chemical, electrolytic, corrosive and mechanical action.

10 It is particularly aimed to provide a device of this character which will facilitate the work of searching parties in locating wrecked or missing aircraft.

15 Another aim is to provide such a construction as avoids dependence on fuses or timing devices requiring setting or igniting previous to placing the same in water.

Still another object is to provide a construction 20 of flare which will operate successfully though covered with ice.

Various additional objects and advantages will 25 become apparent from a consideration of the description following taken in connection with accompanying drawings illustrating an operative embodiment.

In said drawings:—

Figure 1 is a view in side elevation showing the flare mounted in a holder;

Figure 2 is a view showing the flare alone, 30 vertically disposed, partly in elevation and partly in section;

Figure 3 is a side elevation showing the flare suspended by a parachute;

Figure 4 is an enlarged longitudinal diametric 35 sectional view through the flare and holder;

Figure 5 is a cross sectional view taken on the line 5—5 of Figure 4;

Figure 6 is a cross sectional view taken on the line 6—6 of Figure 4, and

40 Figure 7 is an enlarged view showing in detail the mounting of the cartridge and incendiary projectile and adjacent parts.

Referring specifically to the drawings wherein like reference characters designate like or similar parts, the flare is adapted to be removably disposed within a cylindrical holder 10, closed at its lower end 11 and open at its other end or top. Such holder is adapted to be supported or mounted in an inclined position as by means of 45 a conventional bracket 12, the holder being mounted on an aeroplane or any other desired vehicle.

50 Removably disposed within the holder 10 is a flare 13. This flare comprises an outer cylindrical casing 14 intimately but removably telescoped

5 in the holder 10 and it also has an outer cylinder 15 and an inner cylinder 16, all in concentric spaced relation. Casing 14 is closed across the bottom by a wall 17. Cork or other buoyant material as at 18 is located between the casing 14 and outer cylinder of shell 15 and inclined openings 19 are provided in alignment through the holder 10, casing 14, cork 18 and outer shell 15 so that in case of submersion, water may pass 10 through the openings or passages 19 to the space 15 between the inner and outer shells 16 and 15 and which is filled with ammonium chlorid or the like in a dry state as at 20. Adjacent the upper end of the flare, the shells 15 and 16 are 15 spaced apart as by means of an aluminum washer 21 or ring 21 soldered or otherwise connected in a moistureproof manner to the metallic shells 15 and 16.

A water tight closure, for instance of cork, as 20 at 22 is connected to the upper end of the metallic casing 14 engaging the same, and the shells 15 and 16 in a water tight manner.

Screw threaded at 23 to the inner wall of the 25 inner shell 16 is a section 24 of a conical metallic head completed by an outer section 25, screw threaded thereto as at 26. Within the section 25 is a metallic cone or abutment head 27 and depending therefrom is a metallic tube 28 having an enlargement 29 at its inner end and extending 30 and fastened to the inner wall 30 forming the bottom of the inner shell 16. The interior of the cone or head section 27 is filled with a quick 35 acting fulminate or combustible material at 31 which is disposed on fulminate or combustible material 32 within the shell 16, usually slower 40 acting. Section 24 has openings 33 therethrough which are covered by a material destructible by fire, and for instance collodion, celluloid or the like at 34, which when destroyed, permits the entrance of air to the material 31 to aid in its 45 combustion.

Located in the enlargement 29 is a cartridge 35, for instance of the army rifle type and co-acting therewith and extending into the tube 28 proper is an incendiary projectile 36. Cartridge 40 45 is adapted to be fired so as to project the projectile 36 outwardly of the tube 28 with great impact or force against the cone or head 27, thereby firing the fulminate 31 for flaring purposes and also to catapult or eject the flare from 50 the holder 10.

A cup 37 is soldered to the wall 30 and located 55 within the same is the operative end 38 of a firing pin 39, the latter extending slidably through the cup 37 and being adapted to move through an

opening 40 in the wall 30 to engage the cap of the projectile 35 in order to fire it. The firing pin 39 has an abutment on it at 41 engaged by an expansive spring 42 to urge firing movement of the pin but restrained by a screw 43, preferably of zinc, extending through a wall 44 of a hydrogen chamber 45 and screw threaded at 46 into a guide disk 47 on the firing pin, which slidably engages the interior surface of a depending 10 guide sleeve 48 carried by the cup 37. Hydrogen may be supplied through a valve tube 49, from any suitable source into the chamber 45 or any other suitable gas may be employed in lieu thereof. The materials forming the hydrogen chamber 45 are rendered non-corrosive due to the metal of which they are made for instance or if of corrosive metal, they are lined with copper foil or the like.

A cushioning coil spring 50 is located between 20 the closed end of holder 10 and the wall 17 of the casing 14.

The wall at the inner extremity of the space 20 is provided with disks or portions thereof of metal foil or soluble material hermetically connected in place, as at 51 and in order to prevent attack thereof by the dry ammonium chlorid 20, glass wool 52 is preferably interposed as shown.

In order to prevent accidental displacement of the flare from the holder, a metallic wire 53 30 may be fastened to eyelets 54 and 55 provided on such parts, the wire being of such strength as to be readily broken or fractured when the projectile 36 is fired and the flare catapults.

It will be realized that the buoyant cork or other 35 material 18 will cause the apparatus to float in an upright position with the eyelet 54 uppermost and the openings 19 submerged so that water will enter such openings or channels 19 and react with the ammonium chlorid or other chemical at 20, seeping 40 through the glass wool at 52 which chemically acts on the metal foil or soluble material 51, entering the hydrogen chamber 29 and attacking the zinc element 43 whereby it is destroyed and the spring 42 is released so that the firing pin 45 will fire the cartridge 35, projecting projectile 36 against the head 27, causing the flare to catapult from the holder 10, breaking the wire 53, firing the material 31 and 32 and destroying the material 34 so that air enters to assist combustion.

50 One or more of the devices 51 may be fractured manually to set the flare into operation as by impact of a hammer against the outer end of a pin 56 soldered to and bridging the casing 14 and outer shell 15.

55 It is also to be noted that the hydrogen gas 45 will react with the ammonium chlorid at 20 so as to disintegrate or destroy the zinc screw 43, to fire the flare.

In instances where the flare is used to light a 60 certain area as for landings or other purposes, the flare is not carried in a housing or holder such as 10 but is suspended from a conventional parachute as at 58 in Figure 3, the same being fastened to an eyelet 59 of a draw element or rod 60 65 of non-corrosive metal, which slidably but in an air-tight manner passes through openings in the ring 21 and closure 22 and which is fastened to one of the disks 51, the weight of the flare and action of the parachute being sufficient to disrupt or displace such element 51 to enable admixture or chemical reaction of the hydrogen in tank 45 and the ammonium chlorid at 20, to disrupt the screw 43 and thereby permit firing. It will be noted that the parachute suspends the 70 flare at a slight angle to the vertical.

75 Various changes may be resorted to provided they fall within the spirit and scope of the invention.

I claim as my invention:—

1. Apparatus of the class described comprising 5 a flare, a holder in which the flare is disposed, an incendiary projectile carried by the flare, means to fire the projectile, flare material ignitable through the firing of the projectile, and springs means between the holder and flare to 10 lessen the recoil incident to firing.

2. Apparatus of the class described comprising 15 a flare, a holder in which the flare is disposed, an incendiary projectile carried by the flare, means to fire the projectile, flare material ignitable through the firing of the projectile, spring means between the holder and flare to lessen the recoil incident to firing, and means connecting the flare and holder against accidental displacement adapted to be fractured incidental to firing. 20

3. Apparatus of the class described comprising 25 a flare, a holder in which the flare is disposed, an incendiary projectile carried by the flare, means to fire the projectile, flare material ignitable through the firing of the projectile, said flare having a buoyant body and means operable by water entering said body to effect the firing of the projectile.

4. A flare of the class described having a 30 casing, a shell in the casing, a tube in the shell, said casing having combustible material therein, a projectile, and means operable chemically through the admixture of water or gas therewith to effect the firing of the projectile to ignite the combustible material. 35

5. A flare of the class described having a casing, a shell in the casing, a tube in the shell, said casing having combustible material therein, a projectile, means operable chemically through the admixture of water or gas therewith to effect the 40 firing of the projectile to ignite the combustible material, said shell having means destructible by firing to admit air to assist combustion.

6. A flare of the class described having a casing, a shell in the casing, a tube in the shell, 45 said casing having combustible material therein, a projectile, means operable chemically through the admixture of water or gas therewith to effect the firing of the projectile to ignite the combustible material, means about the first shell providing 50 a chamber to contain ammonium chlorid, means extending below the shells to contain hydrogen, partition means between the ammonium chlorid and hydrogen comprising a metallic foil capable of attack by ammonium chlorid, glass 55 wool between the ammonium chlorid and said foil.

7. A flare of the class described having a casing, a shell in the casing, a tube in the shell, said 60 casing having combustible material therein, a projectile, means operable chemically through the admixture of water or gas therewith to effect the firing of the projectile to ignite the combustible material, means about the first shell providing a 65 chamber to contain ammonium chlorid, means extending below the shells to contain hydrogen, partition means between the ammonium chlorid and hydrogen comprising a metallic foil capable of attack by ammonium chlorid, glass wool between the ammonium chlorid and said foil, and a draw element connected to the foil and adapted 70 for connection to a parachute.
